UNITED STATES PATENT OFFICE.

ERNEST O. WILLIAMS, OF NEW YORK, N. Y., ASSIGNOR TO PERFECTION CARD RACK COMPANY,
OF NEW YORK, N. Y.

CARD-RACK.

No. 909,498.

Specification of Letters Patent.

Patented Jan. 12, 1909.

Application filed February 21, 1908. Serial No. 417,133.

To all whom it may concern:

Be it known that I, ERNEST O. WILLIAMS, a citizen of the United States, residing at New York, in the county of New York and 5 State of New York, have invented certain new and useful Improvements in Card-Racks, of which the following is a specification, reference being had to the accompanying drawings.

10 My invention relates to improvements in holders for illustrated post cards, and more particularly to those constructed of wire and adapted to be interlocked with and suspended from each other in a vertical string or chain.

15 The object of the invention is to provide an improved wire card holder of this character in which a number of postal cards or similar articles will be effectively supported in an operative position and from which they may 20 be quickly and easily removed.

With the above and other objects in view, the invention consists of the novel construction hereinafter fully described and claimed, and illustrated in the accompanying drawings, in which—

25 Figure 1 is a perspective view of a group of my improved interlocking holders; Fig. 2 is a front view of one of the holders; and Fig. 3 is a side view of the same.

30 In the drawings 1 denotes one of my improved card holders which I preferably construct of a single piece of wire of suitable length and size according to the size and weight of the cards or articles to be supported. The holder is constructed by bending the wire angularly at its center 2 to provide an upper central member or portion 3 having, at the ends of its upwardly and outwardly inclined arms, angular bends or seats 4, 5 which provide means of suspension for 35 the holder. These seats 4, 5 are formed by bending the wire downwardly to provide vertical back retaining portions or members 6, 7 which are made angular or V-shaped by 40 bending them inwardly at approximately their central points, as shown at 8. At the lower ends of the vertical back portions 6, 7 are formed forwardly extending bottom supporting portions or loops 9, 10 on which the 45 lower edges of the cards rest. From the bottom supporting portions or loops 9, 10 the ends of the wire are bent upwardly and inwardly to provide front retaining portions or members 11, 12, the upper extremities of 50 which are coiled or otherwise suitably shaped

to provide inwardly extending card engaging heads or projections 13. The bottom supporting portions 10 are disposed vertically beneath the angular supporting bends or seats 4, 5 and the resilient front retaining portions or arms 11, 12 are disposed in substantially the same vertical planes and are inclined inwardly or rearwardly so that when the device is not in use the card engaging heads 13 will project into the vertical longitudinal plane of the back members 6, 7 of the device, as clearly illustrated in Fig. 3. The front retaining portions or arms 11, 12 are preferably about half the height of the holder so that their heads 13 are disposed outside of 60 and opposite the central angular bends 8 in the portions or members 6, 7.

In use, a plurality of the holders are interlocked with each other, as shown in Fig. 1, so that they may be suspended from the uppermost one which has its supporting bends 4, 5 engaged with nails or other fastenings on a vertical wall or support, or connected to the ends of a suspending cord or the like which will serve as a swivel that will enable the 65 holders to be swung or turned angularly. The superposed holders are supported from each other by having their angular supporting bends 4, 5 engage the bottom portions or loops 9, 10, as clearly illustrated. Owing to 70 the angular shape of the upper central member 3, it will be seen that the holders will hang squarely from each other or from any other support. By making the back supporting portions or members 6, 7 of angular 75 form and shaping the bottom portions 9, 10 and the front retaining portions or members 11, 12, as set forth, it will be seen that cards may be readily inserted in the holders by bowing or bending the cards longitudinally 80 to a slight extent and inserting their bottom edges between the heads 13 and the angular portions 8 of said members 6, 7, and that cards, when inserted in the holders, will be effectively retained therein but may be 85 quickly and easily removed by simply pulling them upwardly.

The construction of the device is also such that it may be inexpensively produced and may be adapted for receiving cards of 90 different sizes.

Having thus described my invention what I claim is:

1. A holder of the character described formed from wire and having supporting 95

100 which are coiled or otherwise suitably shaped 105

110

bends or seats, back portions, bottom portions, and upwardly and inwardly extending front portions, said back portions being offset laterally at points intermediate their ends 5 and opposite the front portions whereby the upper ends of the latter may spring into the vertical longitudinal plane of said offset back portions for the purpose set forth.

2. A holder of the character described 10 formed from wire and having supporting bends or seats, back portions, bottom portions, upwardly and inwardly extending resilient front portions and inwardly extending card engaging heads at the upper 15 ends of said front portions, said back portions being offset laterally at points intermediate their ends and opposite said front portions whereby the heads of the latter may spring into the vertical longitudinal plane of 20 said offset back portions for the purpose set forth.

3. A holder of the character described 25 formed from a single piece of wire bent angularly at its center to provide a V-shaped central member having at the ends of its diverging arms angular supporting bends or seats, back portions depending from the latter and bent intermediate their ends whereby

their intermediate parts will be offset, bottom supporting portions or loops at the 30 lower ends of the back portions, upwardly and inwardly extending resilient front portions or arms and inwardly projecting engaging heads at the upper ends of said arms adapted to project into the vertical longitudinal plane of the back portions, substantially 35 as and for the purpose set forth.

4. A series of holders of the character described, each formed of wire and having front and back portions united by bottom supporting portions, a central V-shaped member 40 between the upper ends of the back portions and having supporting bends or seats, and engaging heads upon the upper ends of the front portions, the latter extending inwardly, the back portions being bent or offset to allow said heads to project into the vertical longitudinal plane of said back portions, substantially as and for the purpose 45 set forth.

In testimony whereof I hereunto affix my signature in the presence of two witnesses.

ERNEST O. WILLIAMS.
